UNITED STATES PATENT OFFICE.

FRANCIS S. HESSELTINE, OF MELROSE, MASSACHUSETTS.

UMBRELLA-HOLDER.

SPECIFICATION forming part of Letters Patent No. 287,676, dated October 30, 1883.

Application filed April 9, 1883. (No model.)

To all whom it may concern:

Be it known that I, FRANCIS S. HESSELTINE, of Melrose, in the county of Middlesex and State of Massachusetts, have invented a new and useful or Improved Umbrella-Holder, which will, in connection with the accompanying drawings, be hereinafter fully described, and specifically defined in the appended claim.

10 This invention relates to means for supporting or holding umbrellas when folded, and for receiving the drippings therefrom, when so held, if wet; and it consists in the construction and combination of the divers devices embodied therein, as hereinafter more particularly and fully set forth and claimed.

In said drawings, Figure 1 is a front elevation, showing the upper or pivotal supporting-ring and its holder as secured in place 20 for use. Fig. 2 is a side elevation of the parts shown in Fig. 1, the ring being shown depending, as in Fig. 1, by solid lines, and by dotted lines as raised for use. Fig. 3 is a top or plan view of the lower or fixed supporting-ring. Fig. 4 is a similar view of the drip-cup, which is adapted to be interlocked in and supported by the ring shown in Fig. 3. Fig. 5 is a side elevation of the ring shown in Fig. 3 and the cup shown in 25 Fig. 4, the two being shown as interlocked and as in position for use. Fig. 6 is a vertical section taken centrally through the ring and cup in position as shown in Fig. 5. Fig. 7 is a perspective view, showing the aforesaid 30 parts as secured in position upon a vertical support, and as supporting an umbrella which is inserted in the ring and cup.

In said views, A represents the upper ring, which is preferably formed of wire and of sufficient size to receive the umbrella, as shown in Fig. 7. This ring is shown as pivotally supported by its holder B, which is secured by screws to any suitable vertical support. C represents the lower or fixed ring, which is, 40 as shown, formed to be secured to a vertical support, so that its plane shall be permanently at right angles to such support. A drip-cup, D, is formed to be seated in ring C, and is also formed to be interlocked in said ring by 45 means of coinciding recesses in one and projections in the other, as shown, whereby when the cup is so coincidentally seated in the ring

it may by a partial rotation thereof be secured from accidental displacement and spilling of the water therein.

These devices are especially and, in fact, only adapted to be secured to a vertical or nearly-vertical support, such as a chair, settee-back, wall, or other support such as exist in public halls, theaters, churches, cars, dining-saloons, and other places of public resort or assembling where it is impracticable to part with one's umbrella with any well-grounded expectation of ever finding it again, especially if the condition of the weather renders its possession desirable.

By this device each person in any public place may have his umbrella safe within sight, and be relieved from the discomfort of a wet, dripping umbrella near him, and avoid the 70 delay in selecting and risk of recovering it at all from any place of general deposit.

This device is designed, especially, for attachment to the back of a chair or settee, or to any fixed object—as a wall—to hold a single 75 umbrella in such manner that it shall not touch and deface the object nor incommod the sitter, and will retain the drippings from the umbrella in a detachable cup, where it will dry up or may be removed.

One of the peculiar advantages of my invention consists in the fact that the wet umbrella is held out of contact with the vertical support to which rings A and C are attached, as ring A and its holder B isolate the upper 85 portion of the umbrella from such support, and cup D, in which the tip of the umbrella rests, and its supporting-ring C, also serve to hold the umbrella aloof from the vertical support, and hence the moisture with which the 90 umbrella may be saturated is prevented from discolored the varnish or polish which may overlie such support, and which would otherwise be seriously injured and discolored by such moisture.

I am aware of Letters Patent of the United States No. 133,809, dated December 10, 1872, for "Umbrella-Stands for Church-Pews," and I claim nothing shown or described therein, and, on the contrary, disclaim the same, my invention being distinguished therefrom in several particulars, especially in that my drip-cup and its supporting-ring are only adapted to be attached to a vertical or nearly-

vertical support, while the corresponding device in said patent is only designed to be secured, when in use, to the floor, and while my upper ring is adapted to hold the umbrella aloof from the support, the corresponding device in said patent is designed to hold it in direct contact with the support.

I claim as my invention—

An umbrella-holder consisting of two brackets, one being constructed substantially as de-

scribed, whereby it may be attached to a vertical wall and support a drip-cup, and the other having a hinged ring or loop for the support of the upper end of the umbrella, substantially as set forth.
